Morris Fink, Brooklyn, N. Y.

Application June 7, 1954, Serial No. 30,850

Term of patent 14 years

(Cl. D74—17)

To all whom it may concern:

Be it known that I, Morris Fink, a citizen of the United States of America, residing in the Borough of Brooklyn, city of New York, county of Kings, and State of New York, have invented a new, original, and ornamental Design for a Pen, of which the following is a specification, reference being had to the accompanying drawings, forming part hereof.

Figure 1 is a front elevational view of a pen, showing my new design,

Figure 2 is a rear elevational view of the pen shown in Figure 1 as it appears in closed position,

Figure 3 is a top plan view thereof,

Figure 4 is a front elevational view of the clip portion of the pen shown in Figure 1,

Figure 5 is a rear elevational view thereof, and

Figure 6 is a top plan view thereof.

I claim:

The ornamental design for a pen, as shown.
